UNITED STATES PATENT OFFICE.

WILLIAM A. WHEELER, OF INDIANAPOLIS, INDIANA.

MACHINE FOR FORMING CIRCUMFERENTIAL CRIMPS IN SHEET-METAL PIPES.

SPECIFICATION forming part of Letters Patent No. 254,890, dated March 14, 1882.

Application filed November 14, 1881. (No model.)

To all whom it may concern:

Be it known that I, WILLIAM A. WHEELER, of the city of Indianapolis, county of Marion, and State of Indiana, have invented certain new and useful Improvements in Machines for Forming Circumferential Crimps in Sheet-Metal Pipes, of which the following is a specification.

My said invention consists of a machine for forming circumferential crimps in sheet-metal pipes; and it is in some particulars an improvement upon the invention for which Letters Patent No. 224,974 were granted me, bearing date February 24, 1880.

Referring to the accompanying drawings, which are made a part hereof, and on which similar letters of reference indicate similar parts, Figure 1 is a side elevation of a machine embodying my improvements, portions of the frame-work being broken away to show the mechanism more clearly; Fig. 2, a vertical section thereof on the dotted line *u u*; Fig. 3, a top or plan view of the machine; Fig. 4, an under side plan of the top portion of the machine as seen when looking upwardly from the dotted line *v v*; Fig. 5, a top or plan view of the central portion containing the crimping-wheels, the inside stationary rest for the pipe-section being removed; Fig. 6, a detail section on the dotted line *w w*; Fig. 7, a detail view as seen when looking to the left from the dotted line *x x*; Fig. 8, a detail view as seen when looking to the left from the dotted line *y y*; Fig. 9, a detail section on the dotted line *z z*; Fig. 10, a plan view of those portions of the machine below the table as seen when looking downwardly from the dotted line *v v*, and Fig. 11 a front elevation of the bottom portion of the machine as seen when looking at the same from the dotted line at the left of Fig. 1.

In said drawings, the portions marked A, A', A², and B represent the frame-work of the machine; C, the table thereon; D, sliding clamps on said table; E, a circular disk underneath said table, by which the sliding clamps are actuated; F, an inside clamp or rest for the pipe-section; G, an inside stationary rod on which the clamp F is secured; H, a hollow revolving shaft surrounding the rod G, and which

operates a portion of the mechanism; I, a driving-shaft which drives the shaft H through the bevel-gear wheels I' H'; J, a counter-shaft, which is also driven by the shaft I through the cam-wheels I² J²; K, a lever which is operated by the shaft J through the cam-wheel J' and the anti-friction truck K' to operate the disk E, and through it the clamps D; L, a sleeve mounted loosely on the shaft H, and capable of being moved vertically thereon by the cam-wheel J³ and the anti-friction truck L³, but prevented from being rotated thereby by its connection with the arm M, which is rigidly connected thereto; M, an arm running from the block L up past the shaft-bearing on the frame-work B, and which, as it rests closely against said frame-work, between lugs thereon, is prevented from any but a vertical movement; N, a sleeve supported by the arm M upon the upper portion of the hollow shaft H, which is adapted to be moved vertically by said arm, and which forms part of a toggle-joint mechanism for expanding the revolving formers or crimping-wheels; O, a circular head secured to and revolving with the shaft H, which carries the crimping-wheels; P, the crimping-wheels or revolving formers, which form the crimps in the section of pipe; and Q, a treadle by which a detent is released and the working parts put in operation.

The frame A A' A² B is preferably composed of cast-iron parts bolted rigidly together. The parts A' A² serve as bridge-trees and carry the bearings in which the vertical shafts rest, as also the part B, which is in the form of a wing on said parts A' A². Upon the part B are the bearings for the horizontal shafts I J.

The table C rests directly upon the upper ends of the frame parts A, and is rigidly secured thereto. It is provided with adjustable dovetailed slides, (composed of the parts c c' and adjusting-screws c², which pass through bosses c³, as shown,) in which the clamps D move. Brackets C' are secured to the upper side thereof and sustain a ring, C², upon which or projecting points thereon the section of pipe rests when placed in the machine. These brackets are rendered adjustable by the adjusting-screws c⁵, which operate as indicated most plainly in Fig. 2.

The clamps D are each formed of two parts, as shown, one of which is adjustable on the other by means of adjusting-screws d, which pass through bosses d' upon one part and 5 against the ends of or projections upon the other.

The disk E rests inside a flange, c⁴, which projects downwardly from the under side of the table C, and is capable of a rotary movement therein so far as the mechanism will permit. Slots e, which are formed at an angle with the radii of the disk, are formed therein, down through which project studs d² from the lower side of the clamps D. Thus when said 15 disk is rotated said clamps are forced toward or from each other, according to the direction in which the disk is moved.

The inside clamp or rest, F, is secured to the top of the central stationary rod, G. It 20 serves as an inside rest for the section of pipe while it is in the machine and being operated upon. Its lower edge should consist of steel sections, which are secured to the upper or cast-iron parts. By means of the inside threaded 25 sleeve, f', and the cone-shaped nut f² thereon, the sections f can be expanded as they wear by simply turning said nut, and thus add greatly to the durability of these heads F.

The rod G is held in place by being screwed 30 into the stirrup a² on the frame part A', and which practically forms a part thereof. It is adapted to be adjusted up or down by being turned in said stirrup, and when in right position is prevented from moving therefrom by 35 the lock-nut g, which is shown as having a handle for convenience.

The hollow shaft H rests and turns upon a sleeve, H², in the frame part A', and is secured from rising out of its seat in said cylinder by 40 a nut, h², thereon. This shaft is adjustable vertically by means of the bell-crank lever H³ and its screw h³, the operation of which will be readily understood by reference to Fig. 2.

The shaft I is an ordinary driving-shaft and 45 runs in bearings on the frame part B. It bears the tight and loose pulleys I⁴ I³, by which it is driven, the spin-gear I¹, and the bevel-gear I², or their equivalents, for the purposes specified. The counter-shaft J also rests in bearings on 50 the frame part B. It carries the two cam-wheels J' and J³, the loose combined gear and clutch wheel J², and the clutch part J⁴. As the wheel J² is loose on this shaft, said shaft only revolves when the clutch is thrown into 55 gear.

The construction and operation of the clutch J² J⁴ are as follows:

The part J² has projections j² on its inner face, (see Fig. 2,) and the part J⁴ has a spring- 60 bolt, j', which engages therewith as the wheel J² revolves, and thus rotates the shaft J. Pivoted to the outside of the part J⁴ by the pivot j⁵ is the lever J⁵, which engages with a projecting stud, j⁶, on the spring-bolt j', where- 65 by said spring-bolt can be withdrawn from contact with the studs j². Pivoted to the frame

part B by a pivot, b, is a vibrating arm, B', which is operated by the treadle Q and treadle-rod Q', and carries the detent b', which is or may be rendered adjustable by means of a set-screw, b². 70 This detent engages at all times with the lever J⁵, except when forced up by the action of the treadle, and thus holds the spring-bolt j' back out of engagement with the projections j², thereby allowing the wheel J² to revolve loosely on 75 the shaft J and said shaft to remain motionless. When it is desired to revolve the shaft J the detent is forced up out of engagement with the lever by means of the treadle, the spring-bolt flies forward into engagement, and the 80 shaft is thus rotated. As for the purposes of this invention it is only desirable that the shaft J should make one revolution at a time, the detent is allowed to drop back into place immediately after being raised, and thus catches 85 the lever as the parts arrive for the first time at the position from which they started, and disengages the clutch, thereby stopping the motion of the shaft and the parts actuated thereby until such time as it is desired it 90 should revolve again, when the detent is again raised and the operation repeated.

The vibrating lever K is provided with pivots k, which rest in bearings projecting from the frame part B, and is operated by the cam-wheel J' on the shaft J, as will be best understood by reference to Fig. 8. This cam-wheel has its flat side up when the shaft J is at rest, and therefore the lever K occupies at most times a substantially vertical position. The 100 drawings, however, show the detent b' raised and the shaft starting on its revolution. Consequently this lever, like the other parts, is shown in operated position. The lever is connected to the disk E by a connecting-rod, K², 105 which is jointed to both, and to the former preferably by a form of universal joint, as is shown most plainly in Fig. 2, and when it is forced out of vertical position by the cam-wheel thus forces the disk E around a certain 110 distance, and as before explained, by means of the angling slots e in said disk, closes in the clamps D upon the section of pipe which is being operated upon.

The sliding block or sleeve L is operated by 115 the cam-wheel J³ on the shaft J, which comes in contact with the anti-friction truck L³, which is secured to said sleeve by the stud-shaft l³. Like the cam-wheel J', this cam-wheel has its flat side up when the shaft J is at rest, and consequently the sleeve L remains at the lowest point of its movement while the detent b' is engaged with the lever J⁵.

The arm M is secured to the sleeve L by 120 means of the machine-screw m, and is or may be rendered adjustable by means of having the hole through which said screw passes elongated, as shown, and providing an adjusting-screw, m'. This arm is held in position laterally by the projections a' on the frame parts 125 A², between which projections it passes, and which serve as the sides of a slide therefor.

The sleeve N rests in a socket in the upper branch of the arm M, as shown, and is permitted to revolve freely therein, (with the shaft H, to which it is secured by a spline,) while it is as freely permitted to move vertically on said shaft. Upon this sleeve are lips n, to which are pivoted arms n', which are jointed at their other ends to the laterally-movable arms P³, which are rigidly connected to the shafts P², upon which are the arms P', upon which the crimping-wheels or formers P are mounted. Thus an upward movement of the sleeve N (which, as hereinbefore explained, is caused by the cam-wheel L³ and the sleeve L and arm M) will force out the arms n', and through them the arms P³ and P' and the crimping-wheels P, which are thus enabled, as the whole device is continually rotating when the machine is in operation, to bear against the material of the section of pipe which is at the time in the machine, and form a circumferential crimp near the end of said pipe, the shape and size of which are determined by the shape, size, and position of said crimping-wheels or formers.

The circular head O is secured rigidly to the hollow vertical shaft H and revolves therewith. Its principal service is to carry the crimping-wheels and the parts which are immediately connected therewith. Slots o are preferably formed therein, through which the bearings wherein the wheels or formers P rest project, and by which the lateral movement of the same is defined.

The crimping-wheels or revolving formers P rest in sockets p, which in turn rest in bearings in the arms P'. Said wheels are capable of revolving independently of each other and of the shaft G, and are all revolved about said shaft, as indicated. They are held back close to the center of the machine, when not expanded by the means described, by the springs p³, as shown in Figs. 4 and 6. Except in the means of being operated they are not dissimilar to those shown in my Patent No. 224,974, before referred to, and in that are only different in employing a different form of toggle-joint mechanism.

The treadle Q is for the purpose of enabling the operator to readily operate the detent b', as has been before explained. It is pivoted to a depending piece, a³, from the frame part A by a pivot, q, and has an upwardly-projecting rod, Q', attached thereto by the pivot q', which extends up and is attached to the arm B' by the pivot q².

The operation of my invention may be recapitulated as follows: A section of sheet-metal pipe is inserted in the machine, one end passing down between the inside clamp or rest, F, and the outside clamps, D. The treadle is then operated to disengage the detent b'. The shaft I being continually in motion during the operation of the machine, this puts the shaft J in motion, which, through the cam-wheel J', lever K, and disk E, throws the clamps D in-

wardly, firmly clasping the outside of the pipe. The same shaft, through the cam-wheel J³, sleeve L, arm M, sleeve N, and head O, containing the toggle-joint mechanism, expands 70 the revolving formers or crimping-wheels P against the inside of the lower portion of the pipe-section, thus forming a circumferential crimp thereon almost instantaneously. As soon as the cam-wheels come around so that their 75 flat surfaces come in contact with the other parts against which they are intended to operate, the crimping-wheels recede, the jaws D open, and the pipe-section is removed.

Having thus fully described my said invention, what I claim as new, and desire to secure by Letters Patent, is—

1. In a machine for forming circumferential crimps in sheet-metal pipes, a driving-shaft, a counter-shaft, a loosely-running clutch-wheel 85 thereon, which is driven by a wheel on the first shaft, a clutch part on said counter-shaft, provided with a spring-bolt adapted to engage with the clutch-wheel, a lever adapted to disengage said bolt, a detent adapted to operate 90 said lever to effect and maintain such disengagement until purposely withdrawn from contact with said lever, a cam-wheel on said counter-shaft, a lever adapted to be operated by said cam-wheel, and a plate, E, adapted to be operated by said lever, said several parts operating in combination with each other, substantially as set forth.

2. The combination, in a machine for forming circumferential crimps in sheet-metal pipes, 100 of a shaft adapted to rotate intermittently, having a cam-wheel thereon, a vibrating lever operated by said cam-wheel, and a disk adapted to be partially rotated by said lever and connected with the clamps D, which are thereby 105 operated, substantially as set forth.

3. In a machine for forming circumferential crimps in sheet-metal pipes, a disk adapted to partially revolve, and which is provided with slots running at an angle to the radii thereof, 110 through which project points from the clamps D, whereby said clamps, as said disk is turned, are caused to move toward and from a common center, in combination with the lever K and means, substantially as described, for operating the same, substantially as specified, 115 and for the purposes as set forth.

4. The combination, in a machine for forming circumferential crimps in sheet-metal pipes, 120 of a horizontal shaft having a cam-wheel and adapted to revolve intermittently, a vertical shaft having a vertically-moving sleeve thereon, with which (or an anti-friction truck thereon) said cam-wheel will engage, a toggle-joint mechanism, means for connecting said sleeve 125 and said mechanism when they are some distance apart, and a set of revolving formers or crimping-wheels adapted to be expanded from each other by said toggle-joint mechanism, substantially as set forth.

5. The combination, with the crimping-wheel-expanding mechanism of a machine for form-

ing circumferential crimps in sheet-metal pipes and means for operating the same, of the two sleeves L N and a connecting-arm, M, which is capable of adjustment by means of a screw-bolt, 5 m, and an adjusting-screw, m', substantially as set forth.

6. The combination, with crimping mechanism of a machine for forming circumferential crimps in sheet-metal pipes, of the shaft H, 10 the sleeve H², the bell-crank lever H³, and the adjusting-screw h³, whereby said mechanism may be adjusted vertically and the position of the crimps in the pipe thus determined, substantially as set forth.

15 7. The combination of the clamping mechanism of a machine for forming circumferential crimps in sheet-metal pipes, the shaft whereby said mechanism is driven, the clutch parts J² J⁴, the spring-bolt j⁴, which is the 20 means of engagement between said two parts, a lever, J⁵, for withdrawing said bolt, and a detent, b', for operating said lever, substantially as set forth.

8. The combination, with the adjustable segments f, of the inside sleeve, f', and cone-shaped nut f², whereby said segments can be expanded and the size of the working portion of the inside clamp or rest, F, thus increased to compensate for the wear incident to its use or varied to accommodate variations in the size 25 of the pipe to be operated upon, substantially as set forth.

9. The combination, with the ring C², upon which the pipe section rests while in the machine, of the adjustable brackets C', which 30 sustain said ring, and by which the position thereof can be varied, substantially as set forth.

In witness whereof I have hereunto set my hand and seal at Indianapolis, Indiana, this 12th day of November, A. D. 1881.

WILLIAM A. WHEELER. [L. S.]

In presence of—

C. BRADFORD,
C. L. THURBER.
